UNITED STATES PATENT OFFICE.

KANICHIRO KASAI, OF NEW YORK, N. Y.

DESIGN FOR A MIRROR, HAIR-BRUSH, OR SIMILAR TOILET ARTICLE.

53,448.

Specification for Design.

Patented June 17, 1919.

Application filed March 24, 1919. Serial No. 284,874. Term of patent 3½ years.

To all whom it may concern:

Be it known that I, KANICHIRO KASAI, a subject of the Emperor of Japan, residing at New York, county of New York, and State of New York, have invented a new, original, and ornamental Design for Mirrors, Hair-Brushes, or Similar Toilet Articles, of which the following is a specification, reference being had to the accompanying drawing, forming part thereof.

In said drawings:

Figure 1 is a top plan view of my design for mirrors, hair brushes or similar toilet articles;

Fig. 2 is an edge view of the same.

I claim:

The ornamental design for a mirror, hair brush, or similar toilet article as shown.

KANICHIRO KASAI.
